(57) **CLAIM**

The ornamental design for a set of display screens or portions thereof with an animated graphical user interface, as shown and described.

DESCRIPTION

FIG. 1 is a front view of a set of display screens or portions thereof with an animated graphical user interface showing a first image in a sequence according to a first embodiment of the new design;

FIG. 2 is a front view thereof showing a second image in the sequence;

FIG. 3 is a front view thereof showing a third image in the sequence;

FIG. 4 is a front view thereof showing a fourth image in the sequence;

FIG. 5 is a front view of a set of display screens or portions thereof with an animated graphical user interface showing a first image in a sequence according to a second embodiment of the new design;

FIG. 6 is a front view thereof showing a second image in the sequence;

FIG. 7 is a front view thereof showing a third image in the sequence;

FIG. 8 is a front view thereof showing a fourth image in the sequence;

FIG. 9 is a front view of a set of display screens or portions thereof with an animated graphical user interface showing a first image in a sequence according to a third embodiment of the new design;

FIG. 10 is a front view thereof showing a second image in the sequence;

FIG. 11 is a front view thereof showing a third image in the sequence;

FIG. 12 is a front view thereof showing a fourth image in the sequence;

FIG. 13 is a front view of a set of display screens or portions thereof with an animated graphical user interface showing a first image in a sequence according to a fourth embodiment of the new design;

FIG. 14 is a front view thereof showing a second image in the sequence;

FIG. 15 is a front view thereof showing a third image in the sequence;

FIG. 16 is a front view thereof showing a fourth image in the sequence;

(Continued)

FIG. 17 is a front view of a set of display screens or portions thereof with an animated graphical user interface showing a first image in a sequence according to a fifth embodiment of the new design;

FIG. 18 is a front view thereof showing a second image in the sequence;

FIG. 19 is a front view thereof showing a third image in the sequence;

FIG. 20 is a front view thereof showing a fourth image in the sequence;

FIG. 21 is a front view of a set of display screens or portions thereof with an animated graphical user interface showing a first image in a sequence according to a sixth embodiment of the new design;

FIG. 22 is a front view thereof showing a second image in the sequence;

FIG. 23 is a front view thereof showing a third image in the sequence; and,

FIG. 24 is a front view thereof showing a fourth image in the sequence.

The outermost rectangular broken lines in the figures illustrate display screens or portions thereof and form no part of the claimed design. The dash-dot lines in the figures indicate boundaries of the claimed design, and form no part thereof. The claimed design is shown with a symbolic break in its width. The appearance of any portion of the article between the break lines forms no part of the claimed design. The remaining broken lines represent elements of the set of display screens or portions thereof with animated graphical user interfaces that form no part of the claimed design. The appearance of the transitional image sequentially transitions between the images shown in FIGS. 1-4, FIGS. 5-8, FIGS. 9-12, FIGS. 13-16, FIGS. 17-20, and FIGS. 21-24 respectively. The process or period in which one image transitions to another image forms no part of the claimed design. Gray scale shading in the drawings indicates a contrast in appearance. The claim is directed to the collective appearance of the set of display screens or portions thereof.
